Des. 232,179
Patented July 23, 1974

232,179

GAME BOARD

Murray Zaintz, 60 Tynan St., Staten Island, N.Y. 10312

Filed Jan. 15, 1973, Ser. No. 323,851

Term of patent 14 years

Int. Cl. D21—01

U.S. Cl. D34—5 SS

FIG. 1

FIG. 2

FIG. 3

FIG. 4

FIG. 1 is a top perspective view of the game board, showing my new design;

FIG. 2 is a bottom view thereof;

FIG. 3 is a side elevational view thereof, all sides being identical; and

FIG. 4 is a cross-sectional view taken substantially along line 4-4 of FIG. 1.

The dashed lines indicate a continuation of the peripheral square pockets.

I claim:

The ornamental design for a game board, substantially as shown and described
